DOOR CONSTRUCTION

James F. Peelle, Richmond, Ind.

Application July 9, 1934, Serial No. 734,316

6 Claims. (Cl. 20—35)

One object of my invention is the provision of a metal covered door which will withstand extremely high temperatures when exposed to flames being directed thereagainst.

5 Another object of my invention is to provide a door construction which will permit gas, which is generated by heat, to escape from the door without the usual buckling and bulging of the metal covering.

10 Another object of my invention is the provision of a door which will meet with the most exacting requirements of safety ordinances, and to safeguard the lives of the occupants of a building in case of fire.

15 Another object of my invention is the provision of a door construction in which the frame members of the door are secured together, and forming a substantially one-piece door.

20 Still another object of my invention is the provision of a metal covered door which is economical to manufacture and which is attractive in appearance.

Other objects and advantages of my invention will suggest themselves in the course of the following description, and that which is new will be correlated in the appended claims.

25 The most satisfactory manner of carrying out the principles of my invention in a practical, economical, comprehensive and efficient manner is shown in the accompanying one sheet of drawings, in which—

Figure 1 is an elevation of a door embodying my construction.

Figure 2 is a detail cross section taken on the 30 lines 2—2 of Figure 1.

Figure 3 is a detail cross section taken on the line 3—3 of Figure 1.

Figure 4 is a detail cross section taken on the line 4—4 of Figure 1.

40 Figure 5 is a partial elevation of the upper left hand corner of the door, but on an enlarged scale.

Figure 6 is a plan view of the upper left hand edge of the door taken from the line 6—6 of Figure 5.

45 Figure 7 is a detail section taken on the line 7—7 of Figure 5.

Figure 8 is a detail section through one of the stiles before the metal covering is applied thereto.

50 Similar indices designate like parts throughout the several views.

In order that the construction and the advantages of my door may be more fully understood and appreciated, I will now take up a detailed description thereof, in which I will set

forth the same as fully and as comprehensively as I may.

My door is comprised of the usual stiles, rails, and in this instance, a single panel, but embodying my new features of construction.

5 The numerals 1 designate the stiles of my door, the numeral 2 designates the bottom rail of my door, the numeral 3 designates the top rail, and the numeral 4 designates the panel of my door.

10 Each of the stiles of my door is comprised of a core member 5 and the metal sheathing 6. Each of the core members 5 extend the full height of the door, and the metal sheathing 6 extends beyond the ends thereof. Each of the core members 5 has a channeled slot 5' formed therein and extending the full length thereof, and into which the edges of the metal sheathing 6 are turned. Near the ends of each core member 5 mortises are formed, the purpose of which will be hereinafter 15 set forth.

20 The numeral 9 designates a channel member which is preferably formed of sheet metal, said channel member 9 being inserted in the channeled slot 5' before the metal covering is applied thereto. The channel member 9 together with the metal sheathing 6 completely surround the core member 5.

25 The panel 4 of my door is comprised of the central portion 7, and to which the metal covers 8 are secured.

30 The numeral 10 designates the moulding member which is adapted to receive the panel 4. The moulding 10 has the channel-shaped portion 10' formed integral therewith and which is adapted 35 to be inserted between the turned-in edges of the metal covering 6.

35 Both the bottom rail 2 and the top rail 3 have the tenons 2' and 3' respectively formed thereon, and which are adapted to be inserted into the 40 mortises which are formed in the stiles near the ends thereof. The rails 2 and 3 are covered with metal in the same manner as the stile members.

45 In the construction and assembly of my door, the central portion 7 of the panel is secured between the metal covers 8 by glueing under pressure, the moulding members 10 are mitered and the panels are inserted thereinto, after which the mitered portions of the moulding members 10 are welded, thereby forming a continuous frame 50 around the panel. The stiles and rails having been milled to their proper sizes, and the mortises formed therein and near the ends thereof, the tenons being formed thereon respectively, and the channels 9 inserted in the channeled portion 5', 55

are covered separately with metal by drawing the metal and the core through a die simultaneously, the die being adapted to turn the edges of the metal into the channel 5'. The stiles and rails 5 are then assembled around the panel 4 and the moulding 10, the portion 10' being inserted into the channeled slots of the stiles and rails, each of the tenons 2' and 3' being inserted into their respective mortises. The door is then placed in 10 an adjustable form which is adapted to hold the members in clamped relation with each other. While the door is thus held in the clamped position, the nails 11 are driven through the end portions of the rail metal, through the metal sheathing 15 6 and then through the tenons 2' and 3' as shown in Figure 3, thereby securing the rails and stiles together. After the nails 11 are driven into place, the recesses which are formed thereby are filled with solder and then ground smooth 20 thereby presenting an invisible joint between the rails and the stiles, and also forming a joint between the members which has been proven to be practically indestructible under severe tests.

The nails 12 are driven through the metal 25 sheathing of the stiles and rails, through a portion of the core member, through the channel member 9, the moulding portion 10', the panel members 7 and 8, all as shown in Figure 2, and thereby securing these members together and 30 preventing the moulding member 10' from withdrawing from the channeled slots when the door is exposed to excessive heat, such as a door is subjected to in case of fire. After the nails 12 are driven into their respective positions, the recesses 35 formed thereby are filled with solder, which is later ground flush with the adjoining surface of the metal covering.

The portion of the metal sheathing which projects beyond the ends of the stiles is notched, 40 forming the portions 6^a, 6^b and 6^c which are adapted to be folded over the end portions of the stiles. In closing the end portions of the stiles, the portion 6^a is first folded over the end of the core, then the portions 6^b and 6^c are folded 45 over, thereby completely closing the end portions of the stile members. The nails 13 are then driven to secure the portions 6^a, 6^b and 6^c to the end portions of the stiles.

After the door has been assembled, the metal 50 sheathing is pierced and forming the vent holes 14 which are then filled with solder, and which is later ground flush with relation to the surrounding metal sheathing.

When the door is subjected to excessive temperatures caused by flames, the solder is melted 55 out of the vent holes 14 thereby allowing any gas, which might be generated inside the cores, to escape therethrough, and thereby preventing the metal covering or sheathing from bulging.

60 It has been proven by actual tests that my door construction is capable of withstanding extremely high temperatures for an exceptionally long period of time without permitting smoke or flames to escape from the unexposed side of 65 the door, and, due to my construction, the door has unusual strength.

I desire that it be understood that minor 70 changes may be made in the several details of construction herein shown and described, without departing from the spirit of my invention or sacrificing any of the advantages thereof which are new, and which involve invention.

Having now fully shown and described my construction, what I claim and desire to secure by Letters Patent of the United States, is—

1. In the construction of fire-resisting doors, the combination of stile and rail members each 5 having a channeled slot formed therein, channel members inserted into said channeled slots, metal sheathing drawn over the stile and rail members and having its edges turned into said channeled slots, a panel member inserted into a moulding 10 member and together with said moulding member inserted into said channeled slots, and means for retaining said moulding and panel members in said channeled slots, all substantially as shown and described.

2. A fire-resisting door, having in combination, stile and rail members, each of said stile and rail members having a channeled slot formed in one edge thereof, metal sheathing drawn onto the stile and rail members with its edges turned into 20 said channeled slots, a moulding member having a channel portion formed integrally therewith, said channel portion being inserted into the channeled slots of the stile and rail members, a panel member inserted into the moulding mem- 25 ber, a channel member inserted into the channeled slots of the stile and rail members, means for securing all of said members together, and vent holes formed in said metal covering for permitting gas to escape from the enclosed stile and 30 rail members.

3. In the construction of fire-resisting doors, the combination of stile and rail members and metal covering therefor, means for securing the end portions of the metal covering of the rail 35 members through the metal covering of the stile members, and vent holes formed through the metal covering for automatically permitting gas which may be generated by heat to escape from inside the metal covering, all substantially as 40 shown and described.

4. Fire-resisting doors, comprising in combination, wood stile and rail core members and a panel member, metal covering secured on said stile, rail and panel members, vent holes formed 45 in the stile and rail metal, said vent holes being filled with solder which will melt out of said vent holes when exposed to excessive high temperatures and thereby permit the escape of heat-generated gases from within the metal covering. 50

5. In the construction of fire-resisting doors, wood stiles and rails, each having a channel-shaped slot formed longitudinally in one edge thereof, a channel member adapted to be inserted in said channel-shaped slots, pre-formed sheet 55 metal members adapted to cover said stiles and rails and having the edges thereof turned into the channel member and thereby entirely encasing said stiles and rails.

6. In the construction of metal covered fire- 60 resisting doors, means for permitting the escape of heat-generated gases from the interior of the metal covering when the door is exposed to excessive high temperatures, said means comprising 65 vent holes formed in the metal covering and said vent holes being filled with solder, whereby the solder will melt at excessive high temperatures and allow heat-generated gases to escape from within the metal covering through said vent 70 holes.

JAMES F. PEELE.
